FIG. 1 is a top perspective view of a safety valve component for a breastmilk collection system according to the present invention;

FIG. 2 is a top view of the safety valve component for a breastmilk collection system illustrated in FIG. 1;

FIG. 3 is a front view of the safety valve component for a breastmilk collection system illustrated in FIG. 1, the left,
right, and rear views being identical;

FIG. 4 is a bottom view of the safety valve component for a breastmilk collection system illustrated in FIG. 1;

FIG. 5 is a cross-sectional view of the safety valve component for a breastmilk collection system illustrated in FIG. 1,
taken along lines 5-5 of FIG. 2; and,

FIG. 5A is an enlarged view of a stem and valve membrane
of the safety valve component for a breastmilk collection
system illustrated in FIG. 1, showing the stem and valve
membrane in elevation;

The broken lines in the drawings illustrate portions of the
safety valve component for a breastmilk collection system
that form no part of the claimed design.
